AXEL M. WALSTROM, OF MINNEAPOLIS, MINNESOTA

METAL HOOP

Application filed December 19, 1929. Serial No. 415,237.

My invention relates to metal hoops as used on wooden butter tubs and similar coopered containers.

The common type of hoop now in general use is a circular loop of flat metal band which has an outwardly rolled lower edge that forms a bead around the outside of its lower edge, and this bead is provided to form a driving shoulder for the tools which are used in forcing the hoop into place on the tub.

As it is difficult to flare the thin flat bands of the above described common hoops so that they will fit the tapered surface of the tub, they are usually not flared enough and, consequently, the thin upper edge of the hoop is therefore abnormally stressed when the hoop is forced into place on the tapered tub, while its lower edge which is reinforced by the bead, does not touch the tub and is therefore not stressed in the least. The thin upper edge of these hoops is often ruptured by this unequal stressing of the edges of the hoop, and as these hoops are practically non-elastic, they cannot yield sufficiently to prevent rupture when the tubs are swelled to abnormal size by absorbing an excessive amount of moisture.

It is, therefore, an object of my invention to provide a hoop which will adapt itself to the taper of the tub so that both edges of the hoop will be equally tensioned so as to distribute the stress throughout the entire width of said hoop.

It is also an object of my invention to shape the cross-section of the hoop so that it will yield under excessive stress without rupturing.

It is a further object of my invention to provide barbed means on the inside, front edge of my hoop for the purpose of preventing accidental displacement of the hoop while in use.

It is a still further object of my invention to provide a more attractive hoop which will present a smooth, well rounded, and substantial appearance, and in which the overlapping ends will form a smooth joint without exposed edges or rivet heads.

My invention consists of rolling the lower edge of the hoop inwardly into a tubular

bead which, in effect, serves to flare the hoop by reducing the diameter of the lower edge of said hoop.

My invention also consists of providing an inwardly folded upper edge which serves to reinforce said edge and also serves to conceal the raw upper edge of the hoop.

My invention consists, further, of providing barbed means extending inwardly near the upper edge of the hoop and which serve to prevent backward movement of the hoop on the tub.

My invention includes the structure and modification shown and described in the drawings and following specification, and which is specifically pointed out in the annexed claims.

On the drawings:

Fig. 1 is a side elevation of a butter tub having my invention applied thereto.

Fig. 2 is a cross-sectional view of a portion of said tub, taken on line 2-2 of Fig. 1.

Fig. 3 is an inside view of a portion of my improved hoop, and

Fig. 4 is a top edge view of the portion shown in Fig. 3.

Fig. 5 is a diagrammatic, cross-sectional view of my improved hoop, and

Figs. 6 and 7 show a slightly modified form of hoop.

In the several views, numeral 8 indicates a wooden butter tub which is made up of a number of tapered staves that are compressed into a tight, upwardly flared container by a set of three hoops of different size.

This tapered tub acts as a wedge to exert a considerable stress in the hoops as they are forced into place thereon, and most of this stress will be produced in one edge of the hoop unless said hoop is previously flared to fit the tub. To overcome this tendency to abnormally stress one edge of the hoop, I have devised a self-adapting hoop which has inwardly turned edges adapted to yieldingly conform to the taper of the tub.

As shown in Fig. 5 this hoop has an outwardly bulged middle portion 9, and an inwardly rolled lower edge which forms a tubular bead 10 around the entire lower edge of the hoop. A portion of the upper edge of

the hoop is folded inwardly to provide a narrow, downwardly converging flange 11 which terminates in a sharp lower edge 12.

This lower edge 12, is preferably wrinkled 5 during the forming operation so as to provide inwardly extending points 13 which are adapted to bite into the surface of the tub and prevent accidental rearward movement of the hoop, and these wrinkles also tend to make 10 the edge 12 slightly elastic so as to yield more readily while the hoop is being forced into position on the tub.

In the production of these hoops, a suitable length of flat metal band is first formed into 15 a circular loop with its ends over-lapping and joined by spot-welds 14, and this circular band is then placed in a machine where suitable forming rolls shape the hoop to the form shown. This method serves to produce a 20 smooth, telescoped joint, as shown in Figs. 3 and 4, and crimped spots 15 may also be provided to help secure the overlapping ends.

Figs. 6 and 7 show how the upper edge 16 may be turned outwardly to provide a rounded 25 contact surface 17 for engagement with the face of the tub, and a series of barbs 18 may be pressed inwardly in the surface 17 so as to bite into the tub in a manner similar to that of the points 13.

30 In operation:

While the hoop is being forced into place on the tub, the bead 10 and flange 11 will be independently and simultaneously expanded to slightly increased diameters while resisting 35 the outward pressure exerted by the tapered tub, and an approximately equal stress will thus be exerted on both edges of the hoop so that the full strength of the hoops will be employed in drawing the staves together 40 to provide a tight and rigid container.

As shown in Fig. 2, the outwardly bulged portion 9 of the hoop is spaced from the tub for the purpose of making the hoop sufficiently elastic so as to yield under abnormal 45 pressure without rupturing, as an abnormal pressure will only serve to force the bead 10 and flange 11 outwardly and to finally flatten them against the inner face of the portion 9. The space between the portion 9 and 50 the face of the tub is originally sufficient to allow for an abnormal increase in the size of the tub, and this ability to expand to such abnormal size is a very important improvement in my hoop over the common flat band hoop, as the latter cannot expand beyond the elastic limit of the metal itself.

In view of the above description it will be apparent that I have invented a new and useful improvement in metal hoops as specifically pointed out in the following claims.

I claim:

1. A hoop for a tapered tub, comprising: a circular metal band having a shaped major portion spaced from the periphery of said tub and provided with an inwardly rolled

lower edge which forms a hollow inwardly extending and collapsible bead around the lower edge of said hoop and which serves to reduce the diameter of the lower edge of said hoop without flaring said major portion 70 thereof, and the rounded inner edge of said bead being adapted to yieldingly conform to a continuous contact about the periphery of said tub while the upper edge of said hoop is being forced into a tensioned position on said 75 tub.

2. A hoop for a tapered tub, comprising: a circular metal band having its major portion spaced from the periphery of said tub and provided with an inwardly rolled lower edge 80 which forms an inwardly extending collapsible bead around the lower edge of said hoop and which is adapted to yieldingly conform to a continuous contact about the periphery of said tub while the upper edge of said hoop 85 is being forced into a tensioned position thereon, and barbed means provided near the upper edge of said hoop to oppose backward movement of said hoop on said tub.

3. A hoop for a tapered tub, comprising: a circular metal band having its major portion spaced from the periphery of said tub, an inwardly rolled lower edge forming a collapsible bead around the inside of said band and which serves to reduce the diameter of 90 the lower edge of said hoop, an inwardly folded flange provided on the upper edge of said band and arranged so that only the lower edge of said flange normally engages the periphery of said tub, and said bead and 95 the lower edge of said flange being independently adapted to yieldingly conform to a tensioned contact about the periphery of said tub when said hoop is forced into position thereon. 100

4. A hoop for a tapered tub, comprising: a circular metal band having its major portion spaced from the periphery of said tub, an inwardly rolled lower edge forming a collapsible bead around the inside of said band 110 and which serves to reduce the diameter of the lower edge of said hoop, an inwardly folded flange provided on the upper edge of said band, and an inwardly directed lower edge on said flange which is shaped to bite 115 into the surface of said tub so as to oppose backward movement of said hoop on said tub.

5. A self-adapting hoop for a tapered tub, comprising: a circular metal band having a non-flaring major portion spaced from the periphery of said tub, an inwardly rolled lower edge forming a collapsible bead which extends inwardly around the lower edge of said band and which serves to flare said hoop 120 by reducing the diameter of the lower edge of said hoop without contracting the lower part of said major portion, an inwardly folded flange provided on the upper edge of said band and said flange converging downward- 125 130

ly at an angle of less degree than the taper of said tub so that the lower edge of said flange will be forced against the surface of said tub to oppose backward movement of 5 said hoop thereon, and said collapsible bead and said converging flange being both independently adapted to yieldingly conform to a continuous tensioned contact about the periphery of said tub without distorting the 10 edges of said major portion.

In witness whereof, I have hereunto affixed my signature this 16th day of December, 1929.

AXEL M. WALSTROM.
